CLAIM

The ornamental design for an LED fixture, as shown and described.

DESCRIPTION

FIG. 1 is a perspective top view of an LED fixture having the inventive design;

FIG. 2 is a left side view of the LED fixture shown in FIG. 1;

FIG. 3 is a front side view of the LED fixture shown in FIG. 1;

FIG. 4 is a right side view of the LED fixture shown in FIG. 1;

FIG. 5 is a rear view of the LED fixture shown in FIG. 1; FIG. 6 is a top view of the LED fixture shown in FIG. 1; and, FIG. 7 is a bottom view of the LED fixture shown in FIG. 1.

The broken line disclosure represents portions of the LED fixture which forms no part of the claimed design.
